ELECTRON DISCHARGE DEVICE OF THE
CAVITY RESONATOR TYPE

Erich Nevin Kather, South Lincoln, Mass., assignor to Raytheon Manufacturing Company, Newton, Mass., a corporation of Delaware

Application December 13, 1944, Serial No. 568,008

13 Claims. (Cl. 315—39)

1

This invention relates to electron discharge devices having a plurality of resonant cavities or cavity resonators for generating high frequency oscillations, and more particularly to those for generating ultra-short wave oscillations. As the wave length is determined by the size of the cavity, if it is desired to increase the power of the device without increasing the wave length, it is necessary to increase the number of the cavities. Experience has shown, however, that merely increasing the number of the cavities, if carried beyond a certain point, may result in the production of objectionable phenomena, for example the generation of spurious oscillations and a decrease in the ratio of the energy actually delivered by the device to that actually generated, very little if any of the energy generated in the cavities remote from the cavity containing the usual output coupling loop or other coupling device ever reaching the said coupling device.

One of the objects of the present invention is to provide an improved electron discharge device of the general type above referred to, wherein the increased number of cavities required to deliver the power desired without increasing the wave length may be provided without giving rise to the aforesaid objectionable phenomena.

Another object of the present invention is to provide an electron discharge device of the general type referred to having an improved symmetrical coupling for all of the cavity resonators, by which the ratio of energy actually delivered to that generated by the device is materially increased.

These objects and such other aims and objects of the present invention as may hereinafter appear will be best understood from the following description, taken in connection with the accompanying drawing of one embodiment of the invention herein presented for illustrative purposes.

In the drawing:

Fig. 1 is a central, longitudinal section of an electron discharge device incorporating one illustrative embodiment of the invention;

Fig. 2 is a horizontal cross-section on line 2—2 of Fig. 1 on a somewhat larger scale than that of Fig. 1; and

Fig. 3 is a horizontal cross-section on line 3—3 of Fig. 1.

The invention is herein illustratively shown and described in its application to that type of electron discharge device known as a magnetron.

The illustrative embodiment of the invention shown in the drawing comprises an anode struc-

2

ture including a cylindrical member 2 upon the inner surface of which there is provided a central, cylindrical projection 4 to which are soldered a plurality of suitably spaced, radially disposed anode arms 6, the inner ends of which constitute electron-receiving anode faces 8. Each pair of anode arms 6, with the intervening portion of said cylindrical projection 4, constitute an oscillatory cavity or cavity resonator 10. (See Fig. 2.) Said cylindrical member 2 is hermetically sealed at both ends by suitable means, thus constituting an hermetically sealed envelope. In the illustrative embodiment of the invention shown, pole pieces 12 and 14, serving as hereinafter more fully explained to excite a longitudinal magnetic field in the device, are conveniently used for this purpose. These pole pieces 12 and 14 conveniently comprise a conical portion 16 and a central, cylindrical portion 18 provided with a central, cylindrical bore 20. Said conical portions 16 of said two pole pieces 12 and 14 project into opposite ends, respectively, of said cylindrical member 2, the conical surface of each pole piece being encircled by a slot 22 rectangular in cross-section and fitting over the inner, rectangular edge of the inner wall of said cylindrical member 2 to which it is soldered, preferably with silver solder, thus completing the hermetical sealing of the enclosure. Said cylindrical member 2 and anode arms 6 will preferably be made of copper, said anode arms being conveniently stamped from a sheet of highly conductive copper. The surface of the central cylindrical bore 20 of the pole piece 12 is copper-plated to render it electrically conductive.

The aforesaid anode faces 8 cooperate with a cathode 24 supported substantially centrally of said anode faces, said cathode being preferably of the indirectly-heated, thermionic type. It comprises a conductive wall 24 of nickel or other suitable conductive material, preferably coated with an electron-emissive coating 26 of barium and strontium oxide or other suitable electron-emissive material, and contains a helically wound heater wire 28 of tungsten or other suitable metal connected at one end to the inner surface of the conductive wall 24 of the cathode, the other end being connected to a lead-in conductor 29 of molybdenum or other suitable metal sealed through a glass bead 30 in the outer end of a conductive sleeve 32 of suitable sealing metal embraced in a further conductive sleeve 34, preferably of copper alloy, which supports the cathode 24. Said sleeve 34 is sealed through cup 36 of suitable sealing metal. A further sleeve 36', in

alignment with said cup 36, is soldered at one end to the lower end of the cylindrical portion 18 of the pole piece 14 and is connected at its other end to said cup 36 by a glass seal 40.

Light, protective shields 42 are provided at each end of the cathode 24 to prevent electron beams from being projected outwardly toward said pole pieces 12 and 14 from the cathode. Said shields may be supported in any suitable manner. Herein they are conveniently made integral with the cathode wall.

If the device above described be energized and the pole pieces 12 and 14 be also energized with a magnetic field supplied from an external electromagnet or permanent magnet or other suitable means, oscillations will be set up in said cavities 10. In accordance with the present invention the energy thus developed in said cavities is led out in the following novel manner. Alternate anode arms 6 are electrically connected by suitable means at their upper ends, viewing Fig. 1, to the inner end of a conductor 44 of copper or other suitable conductive metal, coaxial with the cathode and sealed through a glass seal 46, sealed to one end of a sealing tube 48 of suitable sealing metal, the other end of which is brazed to the inner and upper end of the cylindrical portion 18 of said pole piece 12. The intervening anode arms 6, between those connected to said conductor 44, are electrically connected by suitable means at their upper ends to the lower end of said pole piece 12. In the illustrative embodiment of the invention shown, the connection of the alternate anode arms 6 with said conductor 44 is conveniently effected by an electrically conductive member, such as a circular cap comprising a disc 50 having a downwardly projecting flange 52 concentric with the cathode 24 and soldered to said alternate anode arms, the lower end of said conductor 44 being soldered to the center of said disc 50. The connection of the same ends of the intervening anode arms, between those connected to said conductor 44, is conveniently made by an electrically conductive member, such as a sleeve 54, concentric with said flange 52 and 45 soldered at one end to said intervening anode arms and at the other end to said pole piece 12.

A metal strap 56 interconnects the other ends of those anode arms 6 whose upper ends are connected to said conductor 44, and another strap 58 interconnects the ends of the intervening anode arms 6 at that end of the anode.

The flange or inner strap 52 and the sleeve or outer strap 54, and the outer strap 56 and inner strap 58, at the other end of the anode structure, not only perform the function heretofore performed by ordinary strapping, of decreasing any tendency of the device to operate in spurious modes, but the connection of said flange 52 and sleeve 54 to the center conductor 44 and pole piece 12, respectively, owing to the difference in potential between said flange 52 and said sleeve 54, serves to feed the energy generated in said cavities out through a coaxial line herein formed by said center conductor 44 and a suitable outer conductor coaxial therewith and herein conveniently consisting of said pole piece 12, whence it can be supplied to any desired utilizing circuit through any conventional wave guide. For the best results the dimensions of said coaxial line should be such as to produce a substantial impedance match between the tube and the load.

To prevent any diversion of the oscillations and confine them to the aforesaid coaxial line, a suitable choke, such as a circular slot 60 of

one-quarter wave length, will preferably be provided in said pole piece 12. Preferably also a hollow, thin-walled horizontally corrugated section 62 of copper with a small vent 64 will be provided in the copper center conductor 44 to allow for any longitudinal expansion and contraction of the latter responsive to variations in temperature.

The present invention provides a system of symmetrical coupling. It couples into all the resonant cavities equally, so that the ratio of energy absorbed and delivered to that generated by all the cavities is increased. Using both straps also adds to the efficiency of the present device.

Wherever the expression "a plurality" occurs it is to be construed as meaning two or more.

I am aware that the present invention can be embodied in other specific forms without departing from the spirit or essential attributes thereof, and I therefore desire the present description to be considered in all respects as illustrative and not restrictive, reference being had to the appended claims rather than to the aforesaid description to indicate the scope of the invention.

What is claimed is:

1. An electron discharge device comprising a cathode, an anode structure including a plurality of anode arms having electron-receiving portions adjacent said cathode and constituting elements of energy generating cavity resonators interconnecting said electron-receiving portions, an inner and an outer electrically conductive strap, the one electrically interconnecting alternate anode arms and the other electrically interconnecting the intervening anode arms, and an output coupling including said two straps as a part thereof.

2. An electron discharge device comprising a cathode, an anode structure including a plurality of anode arms having electron-receiving portions adjacent said cathode and constituting elements of energy generating cavity resonators interconnecting said electron-receiving portions, a coaxial center and outer conductors forming a coaxial line for conducting oscillations generated by the device out of the latter, an electrically conductive strap interconnecting alternate anode arms and electrically connected to one of said coaxial conductors, and a second electrically conductive strap interconnecting the intervening anode arms and electrically connected to said other coaxial conductor.

3. An electron discharge device comprising a cathode, an anode structure including a plurality of anode arms having electron-receiving portions adjacent said cathode and constituting elements of energy generating cavity resonators interconnecting said electron-receiving portions, center and outer coaxial conductors forming a coaxial line for conducting oscillations generated by the device out of the latter, an electrically conductive circular cap interconnecting alternate anode arms and connected at its center to the center coaxial conductor, and an electrically conductive circular sleeve interconnecting the intervening anode arms and electrically connected to the outer coaxial conductor.

4. An electron discharge device comprising a cathode, an anode structure including a plurality of anode arms having electron-receiving portions adjacent said cathode and constituting elements of energy generating cavity resonators interconnecting said electron-receiving portions, center and outer coaxial conductors forming a coaxial

line for conducting oscillations generated by the device out of the latter, an electrically conductive circular cap and an electrically conductive sleeve coaxial therewith at one end of said anode, said circular cap being connected centrally to said center coaxial conductor and to alternate anode arms, and said electrically conductive sleeve being connected to said outer coaxial conductor and to the intervening anode arms at that end of the anode, and two electrically conductive straps at the other end of said anode structure, the one interconnecting alternate anode arms and the other interconnecting intervening anode arms at that end of the anode structure.

5. An electron discharge device comprising an envelope hermetically sealed at both ends by pole pieces and containing a cathode, an anode including a plurality of anode arms having electron-receiving portions adjacent said cathode and constituting elements of energy generating cavity resonators interconnecting said electron-receiving portions, an inner and an outer electrically conductive strap at each end of said anode structure, alternate and intervening anode arms being interconnected at one end of said anode by the inner and outer strap, respectively, and at the other end by the outer and the inner strap, respectively, the inner strap and outer strap at one end of the anode structure being electrically connected, the former to a conductor extending axially through a bore in one of said pole pieces and the latter to said pole piece, which is electrically conductive, said conductor and said pole piece forming the center conductor and the outer conductor, respectively, of a coaxial line through which oscillations generated by the device may be conducted out of the device.

6. An electron discharge device comprising an envelope hermetically sealed at its ends by pole pieces and containing a cathode, an anode structure including a plurality of anode arms having electron-receiving portions adjacent said cathode and constituting elements of energy generating cavity resonators interconnecting said electron-receiving portions, electrically conductive straps interconnecting the alternate anode arms and the intervening anode arms, respectively, at each end of said anode, the strap interconnecting the alternate anode arms and the strap interconnecting the intervening anode arms at one end of said anode being electrically connected respectively to a conductor extending axially through a bore provided in one of said pole pieces and to said pole piece which is electrically conductive, said conductor and said pole piece forming the center conductor and the outer conductor, respectively, of a coaxial line through which oscillations generated by the device may be conducted out of the device.

7. An electron discharge device comprising a cathode, an anode structure including a plurality of anode arms having electron-receiving portions adjacent said cathode and constituting elements of energy generating cavity resonators interconnecting said electron-receiving portions, coaxial center and outer conductors forming a coaxial line for conducting oscillations generated by the device out of the latter, and output coupling means at one end of said anode incorporating an inner conductive strap interconnecting alternate anode arms and electrically connected to said center conductor and an outer electrically conductive strap interconnecting the intervening

anode arms and electrically connected to said outer conductor.

8. An electron discharge device comprising a cathode, an anode structure including a plurality of anode arms having electron-receiving portions adjacent said cathode and constituting elements of energy generating cavity resonators interconnecting said electron-receiving portions, coaxial center and outer conductors forming a coaxial line for conducting oscillations generated by the device out of the latter, output coupling means at one end of said anode incorporating an inner conductive strap electrically interconnecting alternate anode arms and electrically connected to said center conductor, and an outer electrically conductive strap interconnecting the intervening anode arms and electrically connected to said outer conductor, and at the other end of said anode structure an outer electrically conductive strap interconnecting said alternate anode arms, and an inner electrically conductive strap interconnecting said intervening anode arms.

9. An electron discharge device comprising a cathode, an anode structure including a plurality of anode arms having electron-receiving portions adjacent said cathode and constituting elements of energy generating cavity resonators interconnecting said electron-receiving portions, a coaxial line for conducting oscillations generated by the device out of the latter and incorporating an electrically conductive pole piece and a center conductor extending axially of a bore provided in said pole piece, and output coupling means incorporating an inner and an outer electrically conductive strap, said inner conductive strap interconnecting alternate anode arms and being electrically connected to said center conductor, and said outer electrically conductive strap being electrically connected to said pole piece and interconnecting said intervening anode arms.

10. An electron discharge device comprising a cathode, an anode structure including a plurality of anode arms having electron-receiving portions adjacent said cathode and constituting elements of energy generating cavity resonators interconnecting said electron-receiving portions, a coaxial line for conducting oscillations generated by the device out of the latter and consisting of an outer conductor and a center conductor extending axially of a bore provided in said outer conductor, output coupling means at one end of said anode structure incorporating an inner and an outer electrically conductive strap, said inner conductive strap interconnecting the alternate anode arms and being electrically connected to said center conductor, and said outer electrically conductive strap being connected to said outer conductor and interconnecting the intervening anode arms, and an inner and an outer electrically conductive strap at the other end of said anode structure, the former interconnecting said alternate anode arms and the latter interconnecting said intervening anode arms.

11. An electron discharge device comprising a cathode, an anode structure including a plurality of anode arms surrounding said cathode and having electron-receiving portions adjacent said cathode and constituting elements of energy generating cavity resonators interconnecting said electron-receiving portions, coaxial center and outer conductors forming a coaxial line for conducting oscillations generated by the device out of the latter, output coupling means incorporating

a circular electrically conductive member interconnecting alternate anode arms and connected at its center to said center conductor, and a second electrically conductive circular member coaxial with said first-named member and interconnecting the intervening anode arms and electrically connected to said outer conductor.

12. An electron discharge device comprising a cathode, an anode structure including a plurality of anode arms surrounding said cathode and having electron-receiving portions adjacent said cathode and constituting elements of energy generating cavity resonators interconnecting said electron-receiving portions, coaxial center and outer conductors forming a coaxial line for conducting oscillations generated by the device out of the latter, output coupling means incorporating a circular electrically conductive member interconnecting alternate arms at one end of said anode structure and connected at its center to said center conductor, a second electrically conductive circular member coaxial with said first-named member and interconnecting the intervening anode arms at the same end of said anode structure and electrically connected to said outer conductor, and an outer and an inner electrically conductive strap at the other end of said anode structure interconnecting the alternate and the intervening anode arms, respectively.

13. An electron discharge device comprising: a 30 cathode, an anode structure including a plurality of anode arms having electron-receiving portions adjacent said cathode and constituting elements of energy generating cavity resonators inter-

connecting said electron-receiving portions, center and outer coaxial conductors forming a coaxial line for conducting oscillations generated by the device out of the same, and an electrically conductive circular cap and an electrically conductive sleeve coaxial therewith at one end of said anode said circular cap being connected centrally to said center coaxial conductor and to alternate anode arms, and said electrically conductive sleeve being connected to said outer coaxial conductor and to intervening anode arms.
